(57) **CLAIM**

The ornamental design for a drinking bottle as shown and described.

DESCRIPTION

FIG. 1 is a top perspective view of a drinking bottle showing my new design;

FIG. 2 is a bottom perspective view thereof;

FIG. 3 is a side view thereof;

FIG. 4 is a top view thereof; and,

FIG. 5 is a bottom view thereof.

The broken lines in the drawings depict environmental subject matter only and form no part of the claimed design.
